DRAPER COMPANY, OF HOPEDALE, MASSACHUSETTS, A CORPO-
RATION OF MAINE.

FILLING-EXHAUSTION-INDICATING MECHANISM FOR LOOMS.

No. 821,123.

Specification of Letters Patent.

Patented May 22, 1906.

Application filed September 27, 1905. Serial No. 280,306.

To all whom it may concern:

Be it known that I, CHARLES F. ROPER, a citizen of the United States, and a resident of Hopedale, county of Worcester, State of Massachusetts, have invented an Improvement 5 in Filling-Exhaustion-Indicating Mechanism for Looms, of which the following description, in connection with the accompanying drawings, is a specification, like characters on 10 the drawings representing like parts.

This invention relates to automatic looms of the type wherein the running filling is replenished when required; and it has for its 15 object the production of novel means for detecting and indicating substantial exhaustion of the filling in the running shuttle and thereupon to cause a change in the operation of the loom. Such change may be either the 20 stoppage automatically of the loom or the automatic replenishment of the running shuttle without stopping the loom.

So far as I am aware mechanical exhaustion - indicating devices heretofore devised have been dependent for their operation upon 25 the relative distance between the filling mass in the shuttle and some other particular point at a given point in the motion of the lay. This relative point has sometimes been fixed or located with relation to the loom-frame, at 30 other times with relation to the shuttle, and even with relation to the filling-carrier or bobbin itself. The feeler has detected and indicated when the filling has been exhausted to such an extent that the relative distance 35 between the two points mentioned has become equal to a predetermined amount necessary for the operation of the apparatus. In actual practice a large number of variations have to be considered, due to loose crank- 40 arms, differing positions of the shuttle at the time of feeling, springing of the bobbin in the shuttle, varying sizes of bobbins, and varying angles of the latter with respect to the feeler. These variations cause the detection 45 to take place while there are varying amounts of filling on the filling-carrier or bobbin and at times the detection is too late to cause the desired change in the operation of the loom before total filling exhaustion. In my 50 present invention I have so constructed and arranged the apparatus that the variability in operation, due to the different causes hereinbefore mentioned, has been eliminated.

So far as I am aware the operation of the mechanism embodying my present invention 55 is based on entirely new and novel principles—to wit, the relative softness or penetrability of the filling mass as compared with the material of which the filling-carrier is composed and upon which the filling mass is 60 mounted, and not upon any relative distances whatever.

The feeler device comprehends two members movable relatively to each other and adapted to intermittently coöperate with the 65 filling mass in the shuttle. One member penetrates or sinks into such mass of filling, while the other member impinges against it at each coöperation, with the result that a relative movement of such members is effect- 70 ed. An actuator is inoperatively positioned by such relative movement, and this operation is repeated on each detecting-pick until the filling has been exhausted to a predetermined extent. When this occurs, however, 75 the penetrating member in practice engages the surface of the carrier at the instant the impinging member impinges against the remaining filling, and both members are given a movement in unison, which results in op- 80 erative positioning of the actuator. The latter thereupon acts to effect the actuation of means which change the operation of the loom. I prefer to provide the penetrating member with two penetrating points or ex- 85 tensions, with the impinging member acting between them, so that if either extension engages the harder surface of the filling-carrier the desired action will take place. No ordinary variation in the position of the shuttle, 90 size, or position of the filling-carrier can effect the result in any way, as will be manifest more fully hereinafter. Inasmuch, also, as either of the penetrating extensions can cause the change in the operation of the loom 95 at the proper time, it will be seen that no variation in angle of the filling-carrier in a lateral plane, due to its springing in the shuttle or irregular positioning of the latter in the shuttle-box, will modify the operation of the 100 feeler device or cause it to operate at the wrong time. Such angular variations in practice can and do affect the operation of other feeler devices more or less seriously.

The various novel features of my invention 105 will be fully described in the subjoined

specification, and particularly pointed out in the following claims.

Figure 1 is a top plan view of a portion of a loom having applied thereto filling-exhaustion-indicating mechanism embodying one form of my present invention. Fig. 2 is a left-hand side elevation of the mechanism shown in Fig. 1. Fig. 3 is an enlarged top plan view of the feeler device, showing the penetrating and impinging members thereof and the actuator. Fig. 4 is a longitudinal section thereof on the line 4-4, Fig. 3. Fig. 5 is a detail in plan, showing the manner in which the feeler device operates when there is a substantial amount of filling in the shuttle. Fig. 6 is a longitudinal section thereof on the line 6-6, Fig. 5. Fig. 7 is a similar view, but showing the manner in which the actuator is operatively positioned when the filling is substantially exhausted; and Fig. 8 is a rear view of the transmitter and the feeler device, showing the latch in section on the line 8-8, Fig. 1.

The filling-feeder F, Fig. 2, to contain the filling-carriers or bobbins b on which the mass of filling is wound, the transerrer f', self-threading shuttle S, controlling rock-shaft d' to effect filling replenishment, and the upturned arm d², fast on said rock-shaft and having the pivotally-connected and rearwardly-extended latch d³ to at times coöperate with a vibrating actuator, such as the weft-hammer W, may be and are all of well-known construction. In operation when the rear end of the latch is moved into the path of the head W' of the weft-hammer the forward-swing of the latter pushes the latch forward and acts, through arm d², to turn the rock-shaft d' in the direction of arrow 200, Fig. 2, to effect, as usual, the operation of the replenishing mechanism.

The actuator, latch, rock-shaft, and intervening connections constitute controlling means for the loom and, as herein shown, govern the time of operation of the replenishing mechanism.

The shuttle S has an opening 1 in its side wall to register with the opening 2 in the front wall 3 of the shuttle-box 4 at the detecting side of the loom, (see Fig. 1,) if the shuttle is properly boxed on each detecting-pick, said openings providing for the entrance of the feeling device into the shuttle.

The notched holding-plate 5 for the shipper S^x, Fig. 1, has near its outer end a depending lug 6, on which is secured by a bolt 7 a two-part stand 8 9, chambered at 10, Fig. 4, to receive the cylindrical shank 11 of one of the members of the feeler device. This member, which in some of the following claims I have termed a "carriage," is shaped as an elongated flattened rectangle 12, having an opening 13 therein adjacent its rear end or head 14 and recessed at 15 at the front

end of the opening. (See Figs. 3 and 4.) 65 Adjacent the front end the carriage is cut away to leave a depending transverse shoulder 16, which abuts against the opposed stop-shoulder 17, to be referred to, a projecting spring 18, coiled around the shank 11 within 70 the chamber 10 of the stand, tending to maintain the shoulders in contact. The head 14 of the carriage is provided, as herein shown, with two laterally-separated extensions 19, which are beveled to bring each of 75 the ends down to a blunt and substantially vertical edge, and a longitudinal hole 20 is made in the head between said extensions to receive loosely the other member of the feeler device. This member is shown as a short 80 rod 21, having an impinging head 22 at its rear end between the extensions 19 and extended forward into the opening 13 and threaded at 23 to screw into a block 24, a check-nut 25 holding the member 21 in adjusted position in the block. The latter is shaped to present two lateral shoulders 26, and the front end of the block projecting beyond said shoulders is provided with an elongated transverse slot 27, through which extends the pivot 28 of an actuator 29, the ends of the pivot rocking in holes in the sides of the carriage 12. Said actuator is cut out at 30 to loosely embrace the front end of the block 24, leaving bosses 31, which have shoulders 32, which are opposed to the shoulders 26 on said block, and by reference to Figs. 4, 6, and 7 it will be seen that the shoulders are located above the pivot 28. The forward end of the actuator is transversely notched 90 at 33, and a leaf-spring 34 bears at its free end against the under side of the notched end of the actuator, tending to throw it up into operative position. (Illustrated in Fig. 4 and also in Fig. 7.) The spring is mounted 105 in the recessed portion 15 of the carriage and is held by a suitable screw 35.

A depressor is mounted on the carriage and is herein shown as having an inclined open or loop-like head 36 to loosely embrace the carriage, the cross-bar forming the top of the head being beveled to present substantially a transverse knife-edge 37, located close to the notched end of the actuator, the head having an extension 38 at its lower portion, provided 110 with a cam-face 39 and sliding in the slotted part 40 of the lower or bottom member 8 of the feeler-stand. The shoulder 17, hereinbefore referred to, is on the top of the extension 38 (see Fig. 4) and normally abuts against the rear end of the part 8 of the stand, as shown in Fig. 4. A leaf-spring 41, secured at 42 on the top part 9 of the stand, bears at its free end upon the top of the depressor-head 36 and retains the latter in proper position. 115 The head 36 embraces the rearwardly-extended portions of the part 8 of the stand, and the depressor can slide at times toward 120 125

the front of the loom to thereby cause the operation of the means which control the operation of the loom, as will be explained.

Expansion of the spring 18 moves the member 12 of the feeler rearwardly, and the up tilt given to the actuator 29 by the spring 34 moves the shoulders 32 against the opposed shoulders 26 on the block 24, pushing the latter and the attached member 21 of the feeler 10 device rearwardly in the position shown in Figs. 3 and 4. At such time the impinging head 22 is slightly withdrawn or set forward from the upright edges of the extensions 19 (see Fig. 3) by an amount depending upon 15 the desired exhaustion of filling.

As will be understood by those familiar with "feeler-looms," the filling in the shuttle is intermittently engaged by the detecting device, and herein each time the shuttle is 20 properly boxed in the shuttle-box 4, Fig. 1, the forward beat of the lay causes the penetrating member 12 and the impinging member 21 to enter the shuttle and engage the filling mass b^x on the carrier b . Prior to substantial exhaustion of the filling the two extensions 19 sink into or penetrate the yarn mass on each detecting-pick, as shown in 25 Figs. 5 and 6, so that the yarn between them is impinged against by the head 22 of the member 21, the latter thus being moved forward relatively to the penetrating member and through the shoulders 26 32, rocking the actuator 29 into inoperative position—that is, its notched front end is depressed far 30 enough to pass beneath the knife-edge 37 of the depressor-head as the completion of the forward movement of the lay moves the feeler members forward against the action of spring 18, the differential movement of the members 12 and 21 being effected on each detecting-pick and inoperatively positioning the actuator, as in Fig. 6, until the filling has 35 been exhausted to the predetermined extent. When such point is reached, however, the penetrating extensions 19 come substantially against the relatively hard surface of the filling-carrier practically simultaneously with the impingement of the head 22 against the remaining filling, and as there is not enough 40 of the latter to move the head relatively to the extensions 19 both members 12 and 21 will move forward in unison, as in Fig. 7. Consequently the actuator 29 is not moved from its operative position, and as it is moved 45 forward by the carriage 12 the notch 33 engages the edge 37 of the sliding depressor, sliding the latter forward from the position shown in Fig. 4, and thereupon the cam-face 16 acts to tilt a transmitter and effect a 50 change in the operation of the loom.

The transmitter is shown as a lever 43 44, (clearly shown in Fig. 8,) fulcrumed on a substantially horizontal stud 95, mounted on the holding-plate 5, the arm 43 extending beneath the latch d^3 , and normally the rear end

of the latter is thereby supported below the engaging portion of the head W' of the weft-hammer. A lug 46 at such time bears upon the breast-beam, and the transmitter-arm 44 is bent down and extended beneath the extension 38 of the sliding depressor, as shown in Fig. 4, a beveled face 47 being formed on the said arm 44, upon which the cam-face 39 rests, as in Fig. 4.

When the substantial exhaustion of filling 75 is detected, as has been described, and the actuator slides the depressor forward, the cam-face 39 wipes over the beveled face 47, and thereby depresses the arm 44, rocking or tilting the transmitter on its fulcrum 45, lifting the arm 43 and the latch d^3 into position to be acted upon by the head of the weft-hammer. Thereupon the actuation of the filling-replenishing mechanism is effected in the apparatus herein shown. 85

As has been previously stated, the desired action will be effected if either of the extensions 19 comes in contact with the surface of the carrier on which the filling mass is wound, so that any springing of the carrier in the 90 shuttle or any irregular position of the latter in the box will not vary the immediate action of the exhaustion-indicating mechanism at the proper instant.

As one member of the feeler device penetrates the filling mass until substantial exhaustion thereof and the other member always impinges against the filling, I have referred to the former as the "penetrating" member and the latter as the "impinging" 100 member in some of the following claims.

By setting the head of the impinging member toward or away from the plane in which the vertical edges of the penetrating extensions are located the amount of filling remaining on the filling-carrier when replenishment is effected will be decreased or increased, respectively, the check-nut 25 maintaining the adjustment.

My invention is not restricted to the precise construction and arrangement herein shown and described, as the same may be modified or rearranged in various details by those skilled in the art without departing from the spirit and scope of my invention. 110

Having fully described my invention, what I claim as new, and desire to secure by Letters Patent, is—

1. In a loom, a shuttle to contain a carrier having a mass of filling wound thereon, filling-replenishing mechanism, and means to control the time of its operation, said means including two adjacent and yieldingly-mounted, relatively movable members one of which is adapted to penetrate, and the other 120 to impinge against, the filling mass in the shuttle, to effect relative movement of said members, substantial exhaustion of the filling permitting the penetrating member to engage the carrier and move in unison with 125 130

the impinging member, to cause the operation of the controlling means.

2. In a loom, a shuttle to contain a carrier having a mass of filling wound thereon, filling-replenishing mechanism, and means to control the time of its operation, said means including two adjacent and yieldingly-mounted, relatively movable members one of which is provided with two portions which intermittently penetrate the filling mass, the other member intermittently impinging against the filling between said penetrating portions, to effect relative movement of the said members until substantial exhaustion of the filling, such substantial exhaustion permitting the penetrating portions and the impinging member to simultaneously engage the carrier and the remaining filling, respectively, to thereby move the members in unison and effect the operation of the controlling means.

3. In a loom, a shuttle to contain a carrier having a mass of filling wound thereon, filling-replenishing mechanism, and means to control the time of its operation, said means including a member having a bifurcated end to intermittently penetrate the filling mass, a second member supported by the first-named member and movable relatively thereto and adapted to intermittently impinge against the filling mass between the furcations of the first-named member, to effect relative movement of said members until exhaustion of the filling to a predetermined extent, whereupon the bifurcated member and the impinging member simultaneously engage the carrier and the remaining filling, respectively, to move the members in unison and effect the operation of the controlling means.

4. In a loom, a shuttle adapted to contain a carrier having a mass of filling wound thereon, filling-replenishing mechanism, and means to control the time of its operation, combined with a yieldingly-controlled, reciprocating member adapted to intermittently penetrate and be moved by the filling mass until substantial exhaustion thereof, an impinging member carried by and movable relatively to said penetrating member and adapted to intermittently impinge upon and be moved by the filling mass relatively to said supporting member, and an actuator for the controlling means, relative movement of said members preventing coöperation of said means and the actuator, substantial exhaustion of the filling causing the penetrating member to engage and be moved by the carrier in unison with the impinging member, to thereby effect coöperation between the actuator and the controlling means.

5. In a loom, a shuttle adapted to contain a carrier having a mass of filling wound thereon, filling-replenishing mechanism, and means to control the time of its operation, combined with a yieldingly-controlled, reciprocating member adapted to intermittently penetrate the filling mass at a plurality of points until substantial exhaustion thereof, a relatively movable member to intermittently impinge upon the filling between such points, to effect differential movement of said members, and an actuator for the controlling means, engagement of the two members with the carrier and the remaining filling, respectively, causing the members to move in unison and thereby effect coöperation between the actuator and the controlling means.

6. In a loom, a shuttle adapted to contain a carrier having a mass of filling wound thereon, filling-replenishing mechanism, and means to control the time of its operation, combined with a yieldingly-controlled, reciprocating carriage having two adjacent extensions to intermittently penetrate the filling mass until substantial exhaustion thereof, a feeler supported by and relatively movable on the carriage and adapted to intermittently impinge against the filling between said extensions, whereby differential movement of the carriage and feeler is effected, predetermined exhaustion of the filling permitting substantially simultaneous engagement of the carriage and feeler with the carrier and the filling remaining thereon, respectively, to move carriage and feeler in unison, and a device to effect the operation of the controlling means upon such unison movement.

7. In filling-exhaustion-indicating mechanism for looms, in combination, a feeler device having two relatively movable members adapted respectively to intermittently penetrate and impinge against the filling mass in the shuttle, to thereby effect differential movement of said members until substantial exhaustion of the filling, an actuator mounted on one, and controlled by the other of said members, differential movement of the members rendering the actuator inoperative, and a transmitter, substantial exhaustion of the filling permitting movement of said members in unison, to operatively position the actuator and effect its coöperation with the transmitter.

8. In a loom, in combination, a running shuttle adapted to contain a carrier with a mass of filling wound thereon, and mechanism to automatically replenish the shuttle with filling, combined with a feeler to intermittently impinge against and be moved by the filling, a carriage on which the feeler is mounted relatively movable, said carriage having an extension at each side of the feeler to intermittently penetrate the filling mass until substantial exhaustion thereof, to thereby effect differential movement of the carriage and feeler, an actuator mounted on the carriage and controlled by the feeler, differential movement of carriage and feeler rendering the actuator inoperative, and means to cause the operation of the replenishing mech-

anism by or through the actuator when operatively positioned, substantial exhaustion of the filling causing the extensions of the carriage and the feeler to simultaneously coöperate, respectively, with the carrier and the filling remaining thereon, to effect unison movement of the carriage and feeler and thereby operatively position the actuator.

9. In filling-exhaustion-indicating mechanism for looms, in combination, two adjacent and relatively movable members one of which is adapted to penetrate, and the other to impinge against, the filling mass in the shuttle, to effect relative movement of said members, substantial exhaustion of the filling causing the members to move in unison, and means operated by or through such unison movement to control the operation of the loom.

10. In filling-exhaustion-indicating mechanism for looms, in combination, a feeler device having two relatively movable members one of which is adapted to intermittently penetrate, and the other to impinge against, the filling mass in the shuttle, to effect differential movement of the said members until substantial exhaustion of the filling, such exhaustion of filling causing movement of the members in unison, and filling-replenishing mechanism the operation whereof is effected by or through such unison movement of said members.

11. A controlling mechanism for looms, having two relatively movable members one supporting the other, one of said members being adapted to intermittently penetrate, and the other to impinge against, the filling mass in the shuttle, to effect differential movement of said members until substantial exhaustion of the filling, said members thereupon being moved in unison, and means operated by such unison movement to cause the actuation of the controlling mechanism.

12. In a loom, a shuttle adapted to contain a carrier having a mass of filling wound thereon, means to change the operation of the loom, and a device coöperating with the filling to effect the actuation of said means by or through the relative density of the carrier and the filling thereon when the latter is exhausted to a predetermined extent.

13. In a loom, a shuttle adapted to contain a carrier having a mass of filling wound thereon, means to automatically change the filling in the shuttle, and a device intermittently coöperating with the filling to effect the actuation of the filling - changing means by or through the relative density of the carrier and the filling thereon when the latter is exhausted to a predetermined extent.

14. In a loom, a shuttle adapted to contain a carrier having a mass of filling wound thereon, means to change the operation of the loom, and a feeler device having two relatively movable members adapted respectively to intermittently penetrate and im-

pinge upon the filling mass, to effect differential movement of said members until substantial exhaustion of the filling, the penetrating member engaging the carrier upon such exhaustion and moving in unison with the impinging member, such unison movement effecting the actuation of the means which change the operation of the loom.

15. In a loom, a shuttle adapted to contain a carrier having a mass of filling wound thereon, means to change the operation of the loom, and a feeler device having two relatively movable members adapted respectively to intermittently penetrate and impinge upon the filling mass, to effect differential movement of said members until substantial exhaustion of the filling, one of said members being supported by the other, substantial exhaustion of the filling permitting the penetrating member to engage the carrier and to move in unison with the impinging member, to cause the actuation of the means which change the operation of the loom.

16. In filling-exhaustion-indicating mechanism for looms, in combination, a yielding-sustained reciprocating carriage, adapted to intermittently penetrate the filling mass in the shuttle, a feeler longitudinally movable on the carriage and adapted to intermittently impinge against the filling mass, to effect a differential movement of the carriage and feeler until substantial exhaustion of the filling, a rocking actuator mounted on the carriage and operatively connected with the feeler, movement of the latter relatively to the carriage rendering the actuator inoperative, substantial exhaustion of the filling causing the carriage and feeler to move in unison and thereby to operatively position the actuator, and means to control the operation of the loom, actuated by the actuator when operatively positioned.

17. In filling-exhaustion-indicating mechanism for looms, in combination, a yielding-sustained reciprocating carriage having two bevel-faced extensions to intermittently penetrate the filling mass in the shuttle, a feeler longitudinally movable on the carriage and adapted to intermittently impinge against the filling mass between said extensions, to effect a differential movement of carriage and feeler until substantial exhaustion of the filling, an actuator mounted on the carriage and operatively connected with the feeler, movement of the latter relatively to the carriage rendering the actuator inoperative, substantial exhaustion of the filling causing the carriage and feeler to move in unison and thereby to operatively position the actuator, and means the operation whereof is effected by the actuator when operatively positioned.

18. In a loom provided with automatic filling-replenishing mechanism, and a shuttle adapted to contain a carrier having a mass of filling wound thereon, in combination, a de-

vice intermittently coöperating with such filling mass to effect the actuation of the replenishing mechanism by or through the relative density of the carrier and the filling thereon when the latter is exhausted to a predetermined extent.

In testimony whereof I have signed my

name to this specification in the presence of two subscribing witnesses.
